UNITED STATES PATENT OFFICE.

HILBORNE L. ROOSEVELT, OF NEW YORK, N. Y., AND CHARLES S. HASKELL,
OF PHILADELPHIA, PENNSYLVANIA.

CABINET PIPE-ORGAN.

SPECIFICATION forming part of Letters Patent No. 340,461, dated April 20, 1886.

Application filed January 7, 1885. Serial No. 152,183. (No model.)

To all whom it may concern:

Be it known that we, HILBORNE L. ROOSEVELT, a citizen of the United States, residing in the city of New York, State of New York, and CHARLES S. HASKELL, a citizen of the United States, residing in the city of Philadelphia, State of Pennsylvania, have jointly invented certain Improvements in Cabinet Pipe-Organ, of which the following is a specification.

The object of our invention is the production of a compact and portable pipe-organ of large power and great variety of tone.

Our improvements comprehend a novel construction and arrangement of the key and draw-stop action, a novel blowing apparatus, in which the feeders are directly applied to and so as to form a part of the bottom of the wind-chest, and a novel arrangement and application of a wind-reservoir, the said improvements being all substantially of a character hereinafter set forth.

An organ embodying our invention is represented in the accompanying drawings, and described in this specification, the particular subject-matter claimed as novel being herein-after definitely specified.

In the drawings, Figure 1 is a vertical side sectional elevation of an organ conveniently embodying our improvements and at rest, section being supposed either in the plane of the dotted line *x x* in Fig. 2, and sight being taken from the left-hand side of said figure, or else in the planes of the dotted lines *w w* in Fig. 3, and sight being taken from the right-hand side of said figure. Fig. 2 is a rear elevation of the same, the back panels of the case being removed. Fig. 3 is a horizontal sectional plan of the same, section being supposed either in the plane of the dotted line *y y* of Fig. 2 or in that of the line *z z* of Fig. 1. Figs. 4 and 5 are respectively a side elevation and a top plan view of one of the draw-stops and its draw-stop lever. Figs. 6, 7, 8, and 9 are side sectional elevational fragmentary detailed views of parts of the key and draw-stop actions designed in various phases to illustrate the operation of the draw-stops upon the key-action lever-bars and the operation of the keys upon the key-levers in the different positions of the draw-stops and lever-bars. Fig. 10 is

a fragmentary perspective detail, partly sectional, of a part of the key-action, designed to illustrate the connection of a key and sticker with individual key-levers of different sets and the consequent connection through trackers of different sets of said key with the pallets controlling the throats of different pipes. Fig. 11 is a fragmentary perspective detail, partly sectional, of a part of the key-action, designed to illustrate the connection of individual trackers and of the pallets which said trackers control, with two keys an octave apart upon the board. Fig. 12 is a fragmentary side sectional elevational detail, representing parts of the key and draw-stop actions in the positions which they occupy when given stops are drawn. Fig. 13 is a top plan view of one of the key-action lever-bars.

Similar letters of reference indicate corresponding parts in all the figures.

In the drawings, A represents the case of the organ, and *a* the key-desk thereof. The case is preferably constructed in imitation of the appearance of the cases of upright pianos.

P are the pipes, superimposed in a vertical position upon the wind-chest, and together occupying the full height, breadth, and depth of the rear portion of the casing. Any suitable number of stops of pipes may be employed. In the organ represented two stops are supposed.

C is the wind-chest, which occupies a horizontal position near the lower portion of the case.

D are the bellows feeders, which supply wind to the wind-chest, two of which are employed and respectively connected to the two pedals E E. The feeders, as will be understood by reference to Fig. 1, are applied directly to and form the bottom of the wind-chest, so that under the operation of the pedals they feed direct and without intermediate reservoir into the wind-chest.

In stating that the feeders form the bottom of the wind-chest we mean to be understood as saying that the fixed boards of the feeders form the bottom board of the wind-chest; or, conversely stated, that the bottom board of the wind-chest forms the fixed boards of the feeders, which latter in consequence must of course communicate direct with the wind-

chest through suitable valve-connections. The connection of each movable board of the feeders with its pedal is by means of a strap or kindred flexible connection, *d*, which passes 5 over a pulley, *d*^x, and through the intervention of which the depression of a treadle occasions the lift of the movable board of and the consequent compression of its feeder, while the gravitational return of the movable 10 board of said feeder after its compression occasions the elevation or return of the connected pedal into position for action.

F is the bellows-reservoir, which we apply in a vertical position to the rear of the key-action, and preferably at one end of the case, as shown in Figs. 2 and 3. This reservoir 15 has communication, through the opening *f*, with the wind-chest. The placing of the reservoir in a vertical position to the rear of the key-board action and to the side or end, or even back of, rather than beneath, the wind-chest, enables us to place the wind-chest so 20 low down in the case as to afford the necessary height within the case for even the longest pipes.

The fact of placing the reservoir in the manner described, rather than beneath the wind-chest, of course prevents said reservoir from 25 acting as an equalizer between the wind-chest and the bellows-feeders. This, however, is attended with no disadvantage in the operation of the organ; but, on the contrary, is attended with the great advantage of enabling us, as stated, to employ longer pipes than 30 could otherwise be applied within a case of a given height, and, more than this, to obtain the decided advantage of having the wind forced, under the pressure of the bellows-feeders, direct into the wind-chest, and thence of course 35 direct to pipes, rather than of having it enter the wind-chest under simply the expansive force of the reservoir itself, which is not so great as the direct-acting force of the feeders, the reservoir, it being understood, receiving 40 only the surplus wind from the wind-chest.

c' c' c' c' are the pallet-levers, equipped with the pallets which control the throats of the pipes. These pallet-levers are levers of the first order and are contained within the wind-chest.

G are the keys of the key-board, the same being levers of the second order fulcrumed at *g*, and mounted in the key-desk. Each key rests upon a vertical sticker, *H*, suitably supported in the case, suitably guided for vertical movement under the depression of its key, and resting as to its lower extremity upon a sticker-spring, *h*, which, after the depression of a key and sticker, operates to elevate or 55 re-60 turn them to their normal position.

I I' I' I' are the key-action levers, termed herein the "key-levers," a horizontal series of which, corresponding in number with the number of the keys, constitutes a "set" of 65 key-levers, a predetermined series, corresponding with the number of draw-stops, of which sets is employed. In the organ represented,

as a reference to Figs. 1, 2, 3, 10, 11, and 12, will indicate, four sets of these key-levers are employed. It is, however, of course possible 70 either to lessen or augment the number of sets employed.

It is proper to explain that in the contrivance known as the "octave coupler," which is designated by the letter *J*, and shown in Figs. 1 and 2, two additional sets of key-levers, technically, however, known as "octave-coupler levers," are employed; but as the octave coupler forms no part of our invention, for simplicity of material explanation we will 80 make no further reference either to it or to the said key-levers, which are a component part thereof.

Each key-lever is a lever of the first order, and has its fulcrum midway of its length upon a given key-action lever-bar, termed herein a "lever-bar," and all the key-levers of each set have their fulcrum upon an independent lever-bar, the four of which bars employed are respectively designated *K K' K² K³*. Of course the number of lever-bars must correspond with the number of sets of key-levers, and must be lessened or multiplied therewith. The lever-bars, one of which is shown in plan in Fig. 13, are hinged conveniently, 95 by means of pivot-ears *k*^x at their extremities, to suitable supports in the case, and each lever-bar is provided with an arm, *k*^o, extending rearwardly and away from the pivots of the bar, so as to afford a point of leverage, force applied to which will occasion a slight up and-down movement of said lever-bar about its pivots, so that each bar is practically vertically adjustable. The adjustment—that is to say the lift or drop of the respective lever-bars—is effectuated by the employment of draw-stops *L L' L² L³*, of the following construction: Each draw-stop, and reference is now particularly directed to Figs. 4 and 5, is conveniently composed of a head 100 and of a cylindriform rod or body, *l*, fitted to slide in suitable bearings or ways, *a*^x, formed in the key-slip or other member of the case. The rod of each draw-stop is formed with an inclined plane, *l*^x, upon the surface of which 105 rests and travels the toe *m* of a draw-stop lever, *M*, which latter is conveniently made by bending a piece of wire, after the manner shown in Figs. 4 and 5, to form it into a bell-crank lever, having its fulcrum at *m'* in the 110 key-slip, and the rearwardly-projecting arm of which is prolonged to an extent necessary to cause it to overhang the arm *k*^o of one of the lever-bars, to which bar the said lever is linked or connected by means of a stop-action 115 wire, *N*.

In the organ represented the four central draw-stops are connected, as shown in Fig. 2, with the four lever-bars, a separate stop-action wire, respectively marked *N N' N² N³*, 130 being the link between the respective draw-stop levers and the respective key-lever bars. First assume a particular draw-stop at rest, or in the position represented in Fig. 6; then it

is obvious that when such draw-stop has been drawn out into the position represented in Figs. 8 or 9 the toe of its draw-stop lever will have been caused to travel up the inclined plane upon its rod, and the lever itself will have been deflected, so as, through the instrumentality of its stop-action wire, to have occasioned, as shown in the said figures, the elevation of the particular lever-bar with which said wire is connected—a movement of course resulting in the elevation or, more properly, tilting to a predetermined common inclination of the entire set of key-levers with which said lever-bar is provided. A subsequent return or pushing in of the draw-stop, permitting the descent of the toe of the draw-stop lever upon the incline, will likewise, therefore, occasion the drop of the said lever-bar and its set of key-levers to their normal position, or that represented in Figs. 4 and 6.

It is proper to note here that the lateral or two end draw-stops which appear in Fig. 2 of the drawings are respectively connected with the octave-coupler and with the forte, and therefore do not require further mention herein.

It will now be understood that by the movement of the four central draw-stops, which are those connected with the four key-action lever-bars, any one, any two, any three, or all of said lever-bars may be lifted, so as to occasion the common upward tilt of the set or sets of key-levers which said bar or bars respectively carry, and which tilt is for a purpose now to be explained.

All of the key-action levers composing a given set are parallel with each other, but the levers of adjacent sets (adjacent when considered as to vertical disposition) occupy different relative angular positions—that is, for instance, to say, the key-levers I, which compose the upper set are, as represented in Fig. 3, all disposed at a given common angular inclination—for example, that shown—while all of the key-levers I' of the set of levers immediately beneath the upper set are disposed at a different common angular inclination, or at an inclination which is, for instance, almost right-angular to the inclination of the upper set; and again, in like manner, the levers I² of the third set while parallel with the levers I of the upper set are almost right angular in inclination to the levers I' of the second set, as well as to the levers I³ of the fourth or lower set, which latter are parallel with the levers I' of the second set. Each sticker is connected with one key-lever of each set, so that all of the key-levers of each set are connected, through the medium of the stickers, with all of the keys in the key-board; or, to put it in other words, a given key-lever in each particular set of key-levers is connected with a given key in the key-board. It is manifest, therefore, that when a particular key is depressed the particular key-lever of each set of key-levers with which the sticker of said key is connected will be caused to move about its

fulcrum; or, in other words, that the depression of a given key will necessarily occasion the simultaneous tilting of four of the key-levers in the four sets of key-levers, and this, whether the lever-bars which respectively carry said four key-levers be in their normal position or lifted, one or more, about their pivots by the action of the draw-stops which control them, as will be understood by a reference to Fig. 12.

The connection between the inner ends of the key-levers and the free extremities of the pallet-levers of the wind-chest is by means of vertical rods known as "trackers" or "tracker-wires" O O' O² O³, which we arrange in an organ having two stops of pipes, in the following manner: Two sets of trackers which, in the mounting of the organ, lie respectively in two separate but parallel longitudinal vertical planes, are employed, and each tracker of each set of trackers, excepting, as shown in Fig. 3, the twelve end trackers of the outside end of each set of trackers, is, as shown in Fig. 11, by being passed through the inner ends of respectively connected with two key-levers belonging to two adjacent sets of key-levers, so that each tracker, except the forty-eight end trackers, as above stated, is, by reason of the divergent angular inclination of the key-levers of adjacent sets, connected with two keys an octavo apart upon the board. Now, the key G shown in Fig. 10 is connected by its sticker H with the four independent key-levers I I' I² I³, which are each respectively members of one of the four sets of key-levers. When, therefore, the said key is depressed, so as to depress its sticker, each one of the above-named key-levers is tilted about its fulcrum. The key-levers I and I', which, considered with reference to their attachment to the sticker, occupy divergent angular positions, are longer than the levers I² and I³, and, as shown, respectively connected at their rear ends with the trackers O O' which belong to one set of trackers, while the shorter key-levers I² and I³ are similarly connected with the trackers O² and O³ which belong to the other set of trackers. The trackers O O' are at their lower extremities respectively connected with the pallet-levers c c', which respectively control two pipes, P P', an octave apart in the same stop of pipes. The trackers O² and O³ are in like manner at their lower extremities connected with the pallet-levers c² and c³, which respectively control two pipes, P² P³, an octave apart in a different stop of pipes. It will be obvious, therefore, that since a depression of the key in question will occasion the tilting of all four of the connected key-levers, that then if such tilting shall occasion the elevation of all four trackers, all four of the pipes designated in the two stops will be caused to speak, and in such manner a single key will be caused to perform a quadruple duty in causing four separate pipes of separate stops to speak simultaneously. It is, moreover, to be understood that each one of the trackers of the two

sets of trackers which is connected with two key-levers (and we now omit reference to the twelve outside trackers of each set of trackers, which, as stated, are in communication with 5 but a single key-lever) is, through said two levers and by reason of the divergent inclination, considered with reference to their attachment to said tracker of the said levers, in connection with two different keys of the board which are 10 respectively an octave apart; and this will be more readily understood by referring to Fig. 11, in which it will be seen that the tracker O, which is shown connected with the pallet-lever c, passes through a hole in the inner end of the 15 key-lever I, as well as through a hole in the inner end of the key-lever I', and is provided with two fixed buttons, B B', which, in the normal set of the parts—that is to say, when the lever-bars K K' are in their normal position 20 and not lifted—are sufficiently above the upper surface of the inner end of the said key-levers I I' to permit the depression of the key G or the key G', with which the key-levers I' and I are respectively connected, 25 and the consequent deflection or tilting of said key-levers to be without influence upon the said tracker O and its said pallet-lever c. In like manner the tracker O², which in said Fig. 11 is shown connected with the pallet-lever 30 c², passes through holes in the inner ends of the key-levers I² and I³, which are respectively connected with the keys G' and G, and is similarly provided with buttons B² and B³, which are respectively applied in such manner that in 35 the normal set of the lever-bars K² and K³ a depression of either the key G or G' will occasion a tilt of said key-levers I² and I³, which tilt will yet be without influence upon the tracker O² and its pallet-lever c². It will be 40 finally understood, therefore, that either the key G or the key G', which, as already stated, are an octave apart upon the board, can be made to control either the pallet-lever c or the pallet-lever c², and so cause a pipe in a different stop to speak.

45 In the entire foregoing explanation we have assumed each of the key-action lever-bars to be in its normal position or down, and all of the draw-stops which control said lever-bars to be in; and in this assumed position of parts, as stated it is clear that the depression of the keys will be without influence upon the pipes, the set of the buttons upon the trackers being such that the deflection or tilt of the key-levers occasioned by the depression of the keys is insufficient to occasion any or such an encounter between the inner ends of the key-levers and the said buttons as to cause the lift of the trackers and the opening of the pallets 55 of the pipes. It will therefore be obvious that in order to cause the keys to operate upon the pallets of the pipes it is essential that one or more of the draw-stops should be pulled out and one or more of the key-action lever-bars 60 be thereby lifted, so as to impart a sufficient primal inclination to a given set or sets of key-levers to occasion the encounter of the inner

end of a given lever of such set with the button of a given tracker, and the consequent lifting of the tracker and pallet upon the depression 70 of a given key. This action of controlling the set of the lever-bars will be better understood by a reference to Figs. 6, 7, 8, and 9.

In Fig. 6 the draw-stop L represented is in, and the lever-bar K connected therewith in its 75 normal position. It is obvious that in this position a depression of the key G will simply occasion the tilting of the key-lever I from the position which it is shown as occupying in said Fig. 6 to that which it is shown as occupying 80 in Fig. 7, and that this tilting will of course be without effect upon the pallet-lever c, the button B of the tracker O of which is not in range of said key-lever.

In Fig. 8 the draw-stop L is shown drawn 85 out, and the lever-bar K shown in the position into which it is lifted by such drawing out of the draw-stop. In this position it will be noticed that the button B of the tracker O is against the rear end of the key-lever I, so 90 that when the key G is depressed, as shown in Fig. 9, so as to tilt the key-lever, the latter lifts the button and tracker O and occasions the deflection of the pallet-lever c and the consequent speaking of the pipe which said 95 pallet controls.

Having now described a good construction of an organ embodying our improvements, it will be easily understood that the capability of any particular key for causing any particular pipe or pipes to speak is dependent in the first instance upon the control by the draw-stops of the position of predetermined key-action lever-bars, and that according as one, two, three, or all of these lever-bars are 100 lifted is the connection of the key in question with a given pipe or pipes effected. It will be also obvious that by the predetermined drawing of particular stops a given key can be caused either to sound alone a given pipe 105 or simultaneously to sound two pipes an octave apart either in the same or in different stops of pipes, or simultaneously to sound three, four, or, according to the number of stops, a greater number of pipes, each in a 110 different stop, or by twos, an octave apart in different stops—results never heretofore capable of accomplishment in a pipe-organ.

115 It will be clearly manifest that there are certain modifications and mechanical changes which can be made without departing from the principle of our invention. Thus, for instance, it would be quite possible to arrange the key-action lever-bars so that instead of moving in a slight arc about a radial pivot 120 they should move vertically up and down; thus, also, other forms of draw-stops might be employed to effectuate the lift and drop of said lever-bars; thus, again, the precise construction of the wind-chest and the application 125 of the pipes and pallets thereto might be modified. It is also to be understood that any predetermined number of pipes which the case of the organ is capable of containing 130

may be applied. If desired, two bellows-reservoirs may be applied, one at each end of the case; or the reservoir might be placed along the back of the case, although this would not be a convenient arrangement. The feeders may also, if desired, be driven by hand or by other motive power than pedals.

We have also described an organ containing four sets or banks of key-action levers employed in connection with two stops of pipes. We do not, however, restrict ourselves to four sets of these key-levers, as more or even less than four may be employed, and more than two stops of pipes. It would also be possible to modify the character of the various levers, as such, employed, both as to the keys proper and as to pallet-levers; or, in fact, to adopt all such small work-shop expedients of construction and arrangement of minor parts as are common in piano and organ manufacture. The gist of the construction, however, so far as the key-action is concerned, resides in the crossing of the key-levers, or, more properly, the angling apart of the key-levers of different sets from a common sticker and key, so that a single key is caused to control pipes of either the same or of different stops an octave apart, from which construction as embodied by us is obtained in the most compact form an organ of great variety and disproportionate power of tone.

Having thus described our invention, we claim and desire to secure by Letters Patent—

1. In combination with the wind-chest of a pipe-organ, bellows-feeders applied directly to and forming the bottom of said wind-chest, substantially as and for the purposes set forth.
2. In a cabinet pipe-organ, the combination of a wind-chest placed horizontally in the lower part of the case, pipes superimposed upon said wind-chest, and bellows-feeders applied directly to and forming the bottom of said wind-chest, substantially as and for the purposes set forth.
3. In a pipe-organ, the combination of a wind-chest, bellows-feeders applied directly to and forming the bottom of said wind-chest, and a bellows-reservoir disposed in an upright position and having direct communication with said wind-chest, substantially as and for the purposes set forth.
4. In a cabinet pipe-organ, the combination of a wind-chest placed horizontally in the lower part of the case, pipes superimposed upon said wind-chest, bellows-feeders applied directly to and forming the bottom of said wind-chest, and a bellows-reservoir vertically disposed within the case and having direct communication with the wind-chest, substantially as set forth.
5. In a cabinet pipe organ, the combination of a wind chest placed horizontally in the lower part of the case, pipes superimposed upon said wind-chest, bellows-feeders applied directly to and forming the bottom of said wind-chest, a bellows-reservoir vertically disposed within the case, and a key action or

mechanism for at will causing the movement of a key to control a pipe placed beneath the key-board and in front of the pipes, substantially as set forth. 70

6. In a pipe-organ key-action, a series of sets of key-levers disposed as to the levers of adjacent sets at divergent angular inclinations, but as to the levers of alternate sets in parallelism, and respectively connected as to their respective extremities with stickers and with trackers, substantially as shown and described, and for the purposes specified. 75

7. The combination, in a pipe-organ key-action, of a series of sets of key-levers disposed as to the levers of adjacent sets at divergent angular inclinations, but as to the levers of alternate sets in parallelism, and respectively connected as to their respective extremities 85 with stickers and with trackers, and a series of pivoted lever-bars upon which the respective sets of key-levers have their fulera, substantially as set forth.

8. The combination, in a pipe-organ key-action, of a series of sets of key-levers disposed as to the levers of adjacent sets at divergent angular inclinations, but as to the levers of alternate sets in parallelism, and respectively connected as to their respective extremities 95 with stickers and with trackers, a series of pivoted lever-bars upon which the respective sets of key-levers have their fulera, and a series of draw-stops corresponding in number with the lever-bars and adapted to control the 100 set of said lever-bars with respect to their pivots, substantially as set forth.

9. In a cabinet pipe-organ key-action, the combination of a board of keys, a series of stickers corresponding in number to the keys, 105 a series of sets of key-levers, the levers of each of which sets correspond in number with the stickers and are disposed in adjacent sets at divergent angular inclinations, but in alternate sets in parallelism, and a series of trackers arranged and connected with the key-levers, substantially in the manner hereinbefore set forth, and controlling the pallet-levers of the 110 pipes, substantially as described.

10. In a cabinet pipe-organ key-action, the combination of a board of keys, a series of stickers corresponding in number to the keys, 115 a series of sets of key-levers, the levers of each of which sets correspond in number with the stickers and are disposed in adjacent sets at 120 divergent angular inclinations, but in alternate sets in parallelism, a series of trackers arranged and connected with the key-levers, substantially in the manner hereinbefore set forth, and controlling the pallet-levers of the 125 pipes, and a series of pivoted lever-bars upon which the respective sets of key-levers have their fulera, substantially as described.

11. In a cabinet pipe-organ key-action, the combination of a board of keys, a series of 130 stickers corresponding in number to the keys, a series of sets of key-levers, the levers of each of which sets correspond in number with the stickers and are disposed in adjacent sets at

divergent angular inclinations, but in alternate sets in parallelism, a series of trackers arranged and connected with the key-levers, substantially in the manner hereinbefore set forth, and controlling the pallet-levers of the pipes, a series of pivoted lever-bars upon which the respective sets of key-levers have their fulera, and a series of draw-stops corresponding in number with the lever-bars and adapted to control the set of said lever-bars with respect to their pivots, substantially as set forth.

12. In a cabinet pipe-organ, the combination of a board of keys, each of which is connected with a given sticker, and through the medium of said sticker with a series of key-levers belonging to different sets of key-levers disposed as to the levers of adjacent sets at divergent angular inclinations, but as to the levers of alternate sets in parallelism, a series of stickers, a series of sets of key-levers, and a series of trackers controlling the pallet-levers of pipes an octave apart either in the same or in different stops with given trackers, of which series given key-levers of adjacent sets having a common sticker are respectively connected, substantially as hereinbefore set forth.

13. In a cabinet pipe-organ key-action, the combination of a series of sets of key-levers disposed as to the levers of adjacent sets at divergent angular inclinations, but as to the levers of alternate sets in parallelism, a series of pivoted lever-bars upon which the respective sets of key-levers have their fulera, a series of draw-stops corresponding in number with the lever-bars and adapted to control the set of said lever-bars with respect to their pivots,

and a series of trackers connected with pallet-levers of the pipes passing through holes in the inner ends of the key-levers, and equipped with buttons, which in the normal set of the parts are beyond range of contact with the key-levers when deflected by the keys, and which are only in range of given key-levers when the lever-bars of said levers are lifted by the action of a draw-stop, substantially as set forth.

14. The combination, in a pipe-organ key-action, of a series of sets of key-levers disposed as to the levers of adjacent sets at divergent angular inclinations, but as to the levers of alternate sets in parallelism, all of the levers of adjacent sets being of corresponding lengths rearwardly from their fulera, but the lengths of all the levers of given alternate sets being different, and a series of sets of trackers disposed by sets in parallel longitudinal planes, and by sets connected with key-levers of given lengths, substantially as set forth.

15. The combination of a draw-stop having an incline upon its rod or body, a draw-stop lever, one part of which rests and travels upon said incline, a stop-action wire, and a pivoted key-action lever-bar, substantially as and for the purposes set forth.

In testimony whereof we have hereunto signed our names this 16th day of December, A. D. 1884.

HILBORNE L. ROOSEVELT.
CHARLES S. HASKELL.
